UNITED STATES PATENT OFFICE.

CHARLES A. HAGUE, OF CHICAGO, ILLINOIS, ASSIGNOR TO FURST & BRADLEY MANUFACTURING COMPANY, OF SAME PLACE.

JOINTER.

SPECIFICATION forming part of Letters Patent No. 243,124, dated June 21, 1881.

Application filed October 22, 1880. (No model.)

To all whom it may concern:

Be it known that I, CHARLES A. HAGUE, residing at Chicago, in the county of Cook and State of Illinois, and a citizen of the United States, have invented new and useful Improvements in Jointers or Skim-Colters, of which the following is a full description, reference being had to the accompanying drawings, in which—

10 Figure 1 is a side elevation of the landside; Fig. 2, a vertical cross-section on line *x x* of Fig. 1; Fig. 3, a bottom or under view, and Fig. 4 a top or plan view with the mold-board broken off.
15 The object of this invention is to improve the construction of that class of colters commonly known as "skim-colters," and to improve their vertical and lateral adjustments; and its nature consists in an improved construction of the parts, and in so connecting the colter to the beam that it can be raised or lowered as a whole and adjusted in pitch and side draft by the same devices.

20 In the drawings, A indicates a cross-section of a plow-beam; B, the front bracket; C, a cast plate having horizontal flanges fitting against the top and bottom of the beam; D, the rear bracket; E, the brace-landside; F, the point; G, the mold-board; *a, b, c, d, l, and m*, bolts; 25 *e, f, g, and h*, slots; and *i j k* lateral projections on the bracing landside.

30 The brackets B and D are made of wrought-iron or of malleable cast-iron, and are provided with slots *g* and *h* in their vertical parts, and their lower ends are bent or turned under the plow-beam, as shown at Fig. 2. Between the first bracket, B, and the beam I place a cast plate, C, to prevent the wearing of the beam and to hold the bracket steady. This plate 35 C is provided with horizontal flanges fitting against the beam above and below. A similar plate may be used for the rear bracket, D; but as the strain is much lighter on this bracket I have not found it necessary to apply one.

40 The back of the plate may be provided with vertical ears or ribs to steady the bracket, as shown at Fig. 4. The plate E is cast in the form shown, its lower and front end serving

as a landside, and its upper rear end as a brace and as means for connecting with the 50 brackets. The lower end is provided with a side projection, K, fitted to receive the mold-board G, which is held by the bolt *m*, and the point F, which is held by the bolt *l*.

The mold-board and point may be made in 55 one piece, if desired; but I prefer to make them separate, as shown, so as to renew the point when worn with less expense.

The upper part of the bracing landside is provided with lateral projections *i j*, which fit 60 against the lower parts of the brackets, as shown, and are each provided with slots *f e* for the lateral adjustment of the colter by means of the clamping-bolts *c d*. The height of the colter and its pitch are adjusted by 65 means of the slots *g h* of the brackets and the bolts *a b*.

The device is to be attached to the plow-beam in front of the plow, and as it is adjusted both vertically and laterally it can be applied 70 to all ordinary varieties of plows without being specially constructed for the various heights of plows or variations of beam, the plate C being the only part which requires any special fit, and by the construction shown the colter can 75 be easily and nicely adjusted in height, pitch, and side draft, or either.

What I claim as new, and desire to secure by Letters Patent, is as follows:

1. The vertically-adjustable front and rear 80 brackets, B and D, arranged at the side of the plow-beam, and each having its lower end bent, as described, in combination with the colter E, having the front and rear ends of its upper longitudinal portion connected with the bent 85 ends of the brackets to form two points of connection between the plow-beam and the colter, substantially as described.

2. The combination of the adjustable brackets B D with the bracing landside E, having 90 slotted lateral projections *i j*, substantially as and for the purpose described.

CHAS. A. HAGUE.
